UNITED STATES PATENT OFFICE.

TALBOT G. MARTIN, OF CHICAGO, ILLINOIS, ASSIGNOR TO AUTOMATIC ELECTRIC COMPANY, OF CHICAGO, ILLINOIS, A CORPORATION OF ILLINOIS.

TELEPHONE-EXCHANGE SYSTEM.

1,316,101.

Specification of Letters Patent. Patented Sept. 16, 1919.

Original application filed May 6, 1910, Serial No. 559,814. Renewed December 30, 1916, Serial No. 139,904. Patent No. 1,236,858, dated August 14, 1917. Divided and this application filed March 12, 1917. Serial No. 154,156.

To all whom it may concern:

Be it known that I, TALBOT G. MARTIN, a citizen of the United States of America, and resident of Chicago, Cook county, Illinois, have invented a certain new and useful Improvement in Telephone-Exchange Systems, of which the following is a specification.

My invention relates to telephone systems in general, but more particularly to automatic or semi-automatic systems, as it may be used in systems in which the connection is entirely automatic, or in systems in which a calling connection is established by means of both manual and automatic apparatus.

It also relates, more specifically considered, to measured service systems—that is to say, systems in which some provision is made for assessing toll for each successful call, either by the use of a coin or check-controlled mechanism at the substation, or by the use of a registering mechanism located either at the substation or the central station.

My invention contemplates, for example, a system in which the said connectors are provided with means for reversing the talking current in a portion of the talking circuit, when the called subscriber answers, for any suitable or desired purpose.

It also contemplates a system in which automatic connectors and repeaters are employed, the said connectors being provided with means for including resistance in series with a portion of the line or talking circuit when the called line is found, and the said repeaters being provided with similar means for including resistance in series with another portion of the talking circuit when the called line is found, whereby a supervisory signal is displayed at the cord circuit of the originating operator, indicating that the connection has been completed, which signal is then retired when the called subscriber answers.

It further contemplates a system in which the finding of the called line serves, in the manner just explained, to give a signal at the switchboard of the originating operator to show that the desired connection has been completed, and in which the response of the

called subscriber not only retires the said signal to show that the call has been answered, but also serves to operate a measured service device, such as a registering mechanism, which measured service device 55 can be located at any suitable point in the connection, as will hereinafter more fully appear.

My invention also contemplates a rotary connector, *i. e.*, a connector having means 60 for automatically selecting an idle one of a group of lines, having provisions for reversing the current in the calling side of the talking circuit when the called subscriber answers, for any suitable or desired purpose. 65

It also contemplates certain novel details and combinations and features of improvement tending to increase the general efficiency of a telephone exchange system of this 70 particular character, as will hereinafter more fully appear.

In the accompanying drawings Figure 1 is a diagrammatic view of a portion of the apparatus used in a telephone system embodying the principles of my invention. The apparatus shown in this figure consists of the automatic subscriber's substation A allotted to a line which terminates in the line switch C, there being a master switch 75 D for controlling the plungers of the group of line switches of which the switch C is a member. A meter is also shown at J for registering the calls made by the substation A. At E is shown a first selector, which is 80 one of a group allotted to the trunk lines which are accessible to the group of line switches of which the switch C is a member. 85

Fig. 2 is a similar view of a repeater F and a second selector switch H, this switch 90 being quite similar to the first selector E.

Fig. 3 is a diagrammatic view of a connector I, line switch C' which is similar in construction to the line switch C, and substation A' which is similar to the substation A. 95

Figs. 1, 2 and 3 taken together represent a complete circuit connection established between the two subscribers' substations A and A'.

Fig. 4 is a diagrammatic view of a rotary connector I' which can be used in a system embodying the principles of my invention.

Fig. 5 is a similar view of a manual telephone, together with a suitable cord circuit for connecting to the automatic apparatus referred to in the foregoing figures.

The substation A may be of any suitable or approved type and comprises the usual receiver 2, transmitter 3, switch hook 4, impulse springs 5 and 6, impulse wheel 8, which is secured to a dial (not shown) by means of the shaft 9, ringer 10 and condenser 11.

15 The line switch C is of the general type disclosed in British Patent No. 26,301 of 1906, and in the *American Telephone Journal* of June 6, 1908. This switch is provided with the usual plunger (not shown) attached to the plunger arm 19 which is adapted to be attracted by the magnet 14. This magnet comprises four windings, a line winding 15, a trip or pull-in winding 16, a cut-off winding 17 and an auxiliary winding 18. The magnetic circuit of the winding 16 and 17 is separate from that of the windings 15 and 18, so that the plunger arm 19 and cut-off armature 20 are affected only by the windings 16 and 17, while the windings 15 and 18 control only the armature 21. The winding 16, when energized attracts both the plunger arm 19 and cut-off armature 20, while the winding 17 is strong enough to operate only the cut-off armature 20, but will hold the plunger arm in an operated position after the winding 16 deenergizes. The attraction of the plunger arm 19 by the magnet 14 causes the plunger of the switch to be thrust into a group of springs to force the springs 22, 23, 24, 25 into engagement with the springs 26, 27, 28 and 29, respectively, whereby the line conductors are extended over trunk lines to a selector switch such as the selector E, Fig. 1. Although only one set of springs is shown, each switch C is provided with a number of such sets, each set forming the terminal of a trunk line leading to a selector switch. The plungers of the group of line switches of which the switch C is a member are controlled by a common mechanism D usually called a master switch. This master switch controls the plungers in such a manner that the plungers of all idle line switches

55 always stand in readiness to engage the terminal of an idle trunk line leading to a selector switch. The meter shown at J is individual to the substation A and registers only when the subscriber who has been called 60 by the substation A answers. It comprises the ratchet wheel 61 which is actuated by a pawl on the end of the armature 62, which armature is controlled by the relay 63. This relay is composed of the two windings 64

and 65, either one of which alone will not 65 attract the armature 62, but will hold it in its operated position after it is once attracted.

The master switch D comprises a motor magnet 30 which operates the ratchet wheel 70 34, a bank of contacts *a* and a number of circuit-controlling relays. The master switch bank *a* is provided with a wiper 40 for keeping some one of the individual segments 38, 39, etc., in electrical connection 75 with the common segment 41. By means of a suitable mechanical connection the rotary motion of the ratchet wheel 34 is transmitted to the plunger shaft, giving said shaft an oscillatory motion to move the idle 80 plungers (which, when normal, are in locking engagement with said shaft) back and forth in front of the bank terminals. To the plunger shaft there is rigidly secured a cam or locking plate 33 having on its surface 85 a number of circular openings 36 which are engaged by the pin 33 on the armature 37.

The openings in the cam 33 are so positioned that the pin 33 can engage an opening only when the plungers that are in engagement with the plunger shaft are directly opposite the terminals of a trunk.

The selector switch E is of the general type disclosed in United States Letters Patent No. 815,321, granted March 13, 1906, to 95 Keith, Erickson & Erickson, but, as here shown, is adapted to operate in conjunction with a two-wire system. Among other details the selector comprises a set of wipers 46, 47 and 48 carried upon a shaft (not 100 shown) which has a vertical motion controlled by the vertical magnet 49 and a rotary motion controlled by the rotary magnet 50. The selector also has the usual side switch comprising the wipers 51, 52, 53 and 105 54. The side switch is controlled by the private magnet 55. The operation of the switch is controlled by the calling subscriber through the medium of the double-wound line relay 56. The release magnet 57 is 110 normally disconnected from battery by the separation of springs 58 and 59, which are held out of engagement by the arm 60 as long as the switch shaft is in its lowest position. The mechanism of the selector E 115 is released immediately by the energization of the release magnet, rather than by its deenergization, as shown in said selector patent.

The repeater shown at F, Fig. 2, is used as 120 a means of repeating impulses which are transmitted from a substation of one exchange to operate switches in another exchange. Among other details it comprises the double-wound line relay 68 and slow relays 69 and 70. The relay 70 operates to cut the condensers out of the circuit, while the impulses are being repeated. The repeater 125

also comprises the high resistance relay 71 and the double-wound relay 72.

The selector H, also shown in Fig. 2, is similar to selector E shown in Fig. 1.

- 5 The connector I is of the type disclosed in United States Letters Patent #815,176, granted March 13, 1906, to Keith, Erickson & Erickson, but, like the selectors E and H, is adapted to operate in a two-wire system.
- 10 Like the selectors, the connector has a double-wound line relay 73, vertical magnet 74, rotary magnet 75, private magnet 76 and a side switch. In addition, the connector is provided with a back-bridge relay 77, through which the called subscriber is supplied with talking current, a ringer relay 78, by means of which the generator L may be connected across the line, a high resistance relay 79, a busy locking relay 80 and a current-reversing relay 81. The busy signaling machine O consists of an interrupter 82 and induction coil 83.

The rotary connector I' is similar in construction to the connector I, but differs from it slightly as to circuits and manner of operation. When the wipers of connector I are brought into contact with a desired line in response to the operation of the substation calling device, and if said desired line 30 is busy the wipers of the connector I remain upon the contacts of the called line, but connection is not completed with the said line and the calling subscriber is given a busy signal. When the wipers of connector I' are 35 brought into contact with a busy line, said wipers do not remain in this line, but are automatically rotated to the next or an idle set of contacts. In this way the lines which are connected to the banks of connector I' 40 may be divided into a number of groups, all lines of any group being accessible by calling the number of the first line of said group. The set of bank contacts immediately preceding the contacts of any group of 45 lines is connected to relay 276 and resistance coil 277, as shown in Fig. 4.

The substation A' and line switch C' are similar to substation A and line switch C of Fig. 1.

- 50 As shown in these drawings, there are a number of batteries B, with the positive terminal preferably grounded at G, for supplying the exchanges with the necessary current for talking and operating purposes; 55 but, of course, in actual practice this number may be changed and the arrangements modified in any suitable manner—that is, one battery may be used for operating one exchange and another battery for operating another exchange. Obviously any number 60 and any combination of batteries may be used, depending upon the conditions to be met.

Having thus described the general char-

acter of the apparatus which is used in the 65 system, I will now describe the process by which the subscriber at substation A establishes connection, signals and converses with the subscriber at substation A', whose number we will assume to be 2220. I will also 70 describe how a call is registered on the meters and the method by which the apparatus is restored to normal condition after the conversation is completed.

I will also describe how the subscriber at 75 substation A' may obtain connection with an automatic substation.

In order to call #2220 the subscriber at substation A must remove his receiver and operate his dial once for each of the four 80 digits 2—2—2—0. As soon as the receiver is removed from the hook the ringer circuit, which is normally bridged across the line, is broken by the separation of the springs 85 and 86, but a circuit is completed 85 through the transmitter and receiver in series by the closing of the springs 85 and 87. The engagement of these springs completes a circuit through the line winding 15 of the line switch C. This circuit extends 90 from ground G' through the springs 88 and 89, line conductor 12, springs 85 and 87, impulse springs 5 and 6, receiver 2, transmitter 3, conductor 13, springs 91 and 90, line winding 15 of the magnet 14, contact 95 96 and armature 37 to the battery lead 97. The armature 21 of the magnet 14 is attracted upon the energization of the line winding 15, thereby closing the springs 93 and 88 into contact. The closure of these two 10 springs completes the circuit of the pull-in winding 16 in series with the auxiliary winding 18, said circuit extending from ground G' through the springs 88 and 93, pull-in winding 16, auxiliary winding 18 to the 10 battery lead 97. The winding 16, upon energizing, attracts the armature 20, which separates the springs 89 and 91 from the springs 88 and 90, respectively, thus opening the circuit of the line winding 15. The 11 armature 21 cannot fall back, however, until the winding 18 is short-circuited through the springs 107 and 109 by the operation of the plunger arm 19, which may be a little slower in its action than the relay armature 11 20. The attraction of the plunger arm 19 also serves to thrust the plunger in the bank of springs, closing the springs 22, 23, 24 and 25 into contact with the springs 26, 27, 28 and 29, thus extending the line conductors 12 and 13 to the selector E, as previously explained. As soon as these conductors are extended, however, a circuit is completed through the double-wound line relay 56 of the selector. This circuit extends from 1 ground G' through the lower winding of the relay 56, side switch wiper 54 (in first position), springs 29 and 25, conductor 12

through the substation A in the manner previously described, back over conductor 13, winding 64 of the meter magnet 63, springs 22 and 26, side switch wiper 51 and 5 upper winding of the relay 56 to the battery lead 97, thence through battery B to ground G. The energization of the relay 56 shifts the spring 98 out of engagement with the spring 99 and into engagement 10 with the spring 100. This serves to close the circuit of the release relay 101. This circuit extends from ground G³ through the springs 99 and 100 and relay 101 to the battery lead 97, thence through battery B to 15 ground G. The energization of the relay 101 shifts the spring 103 out of engagement with the spring 102 and into engagement with the spring 104, and also closes the springs 105 and 106 into contact. The engagement of the springs 105 and 106 closes an energizing circuit through the holding winding 17 of the magnet 14 of the line switch C. This circuit extends from ground G⁴ through the springs 106 and 105, springs 20 25 and 23, through the holding winding 17 to the battery lead 97, thence through battery B to ground G. The energization of the winding 17 serves to hold the armature 20 and plunger arm 19 in an operated position (as they have not yet been released, due to the slow action of armature 21.)

While the plunger arm 19 is in its operated position it holds springs 107, 108 and 109 in engagement, which short-circuits 35 winding 18, as has been explained, and also provides an energizing circuit for the winding 65 of the meter relay 63. This circuit extends from ground G⁴ through springs 106 and 105 of the relay 101 of selector E, 40 line switch bank springs 27 and 23, winding 65 and springs 108, 109 and 107 to battery lead 97, thence through battery B to ground G. The current in winding 65 is at this time opposed by the current in winding 64 45 and the meter is not operated.

The energization of relay 101 also serves to place a guarding potential upon the private bank contact of the calling line in the banks of all of the connector switches which 50 have access to the group of lines of which that of substation A is a member. The contacts of the connector banks of the said group are multiplied, so that a guarding potential placed on one contact of one connector bank will also be placed on the same contact of the banks of all the connectors of 55 said group. This guarding potential extends from ground G⁴ to the line switch bank spring 23, as has been previously traced, and thence over conductor 110 to the connector private bank contacts.

Let us return now to the operation of the master switch D when subscriber A removes his receiver. As has been stated, he

plunger forces spring 24 into engagement 65 with the spring 28, which completes an energizing circuit through the master switch relay 31. This circuit extends from ground G⁵ through springs 24, 28, segment 38, wiper 40, common segment 41, through relay 31 to 70 battery. The relay 31, upon energizing, completes an energizing circuit through relay 32, which attracts its armature 37, pulling the pin 35 from the opening in the locking plate 33. It also closes an energizing 75 circuit through the motor magnet 30. This circuit extends from ground G⁶ through the motor magnet 30, interrupter springs 43 and 42, contact point 111 and armature 37 to battery lead 97, thence through battery B 80 to ground G. As the armature 44 is attracted it breaks the circuit of the said magnet 30, causing a buzzer action, thus giving the ratchet wheel a step-by-step rotary motion. The motion of the ratchet wheel is 85 transmitted to the plunger shaft, which operates to move the idle plungers from the position in front of the trunk seized by the line switch C. After the plungers have moved a short distance the wiper 40, which 90 is attached to the plunger shaft, is moved off the segment 38, which corresponds to the trunk seized by the line switch C.

When the wiper 40 leaves the contact 38 the relay 31, and consequently the relay 32, 95 is deenergized, but the armature 37 cannot fall back because the opening in the cam 33 which was formerly engaged by the pin 35 has passed out of register therewith. Thus, the master switch will continue to operate until 100 the next opening in the cam passes under the pin 35, when the said pin will drop into the opening, thus locking the shaft against further movement, and the armature 37 disengages from contact point 111, thus opening 105 the circuit of the magnet 30. If the next trunk after the one seized by the line switch C had been busy the wiper 40 would have found the corresponding contact, contact 39, for instance, guarded, and would have maintained 110 the circuit of the relays 31 and 32 while the next opening in the cam was passing under the pin 35. Thus, the master switch would have continued to advance the plungers past the busy trunk. The armature 37 also operates to disconnect the battery from the line winding 15 of all of the switches C which are controlled by the master switch D, and to connect the busy signaling machine with all of the idle lines 115 through their line windings 15 and springs 90 and 91.

The foregoing operations take place immediately upon the removal of the receiver from the hook at the calling substation and 120 before the impulses are sent in for the first digit of the desired number. When the calling device is operated for the first digit 2

the impulse springs 5 and 6 are separated twice momentarily. The separation of the springs 5 and 6 breaks the energizing circuit of the line relay 56 of the selector switch E.

5 The relay 56, upon deenergizing, permits spring 98 to break contact with spring 100 and come into contact with spring 99, thereby completing an energizing circuit through the vertical magnet 49 in series with the

10 private magnet relay 112. As the relay 101 is slow acting it does not deenergize during the momentary breaking of its circuit at the springs 98 and 100. Therefore, the circuit through the vertical magnet extends

15 from ground G^3 through the springs 98 and 99, 103 and 104, slow relay 112, vertical magnet 49 and side switch wiper 52 (in first position) to the battery lead 97, thence through battery B to ground G. The slow

20 relay 112 operates to close an energizing circuit through the private magnet 55. This circuit extends from ground G^3 through the springs 113 and 114 and private magnet 55 to the battery lead 97, thence through

25 battery B to ground G. The relay 112 being slow does not deenergize during the momentary breaking of its circuit as the digit 2 is being called. The vertical magnet operates twice to lift the shaft (not shown) two steps, carrying the wipers 46,

30 47 and 48 opposite the second level of bank contacts, which level contains terminals of trunk lines leading to repeaters F. As soon as the shaft leaves its lowest position the

35 arm 60 is lifted from the spring 59, allowing spring 59 to come into contact with spring 58 to provide the release magnet 57 with a battery connection. After the last impulse is delivered to the vertical magnet

40 49 the relay 112 has time to deenergize, thereby breaking the circuit of the private magnet 55 which controls the side switch. As this magnet deenergizes it permits the side switch wipers to pass to second position.

45 In second position the side switch disconnects battery from vertical magnets and completes an energizing circuit through the rotary magnet 50 in series with the slow acting guarding relay 115. This circuit extends from ground G^2 through interrupter

50 springs 116, rotary magnet 50, slow relay 115 and side switch wiper 52 to battery lead 97, thence through battery B to ground G. The rotary magnet armature operates once

55 to rotate the wipers 46, 47 and 48 one step onto the bank contacts, to press down the private magnet armature, and to open its own circuit at the interrupter springs 116. The circuit of the rotary magnet being thus

60 opened, the rotary armature falls back. If the first trunk upon the contacts of which the wipers have just been rotated is not busy, the private armature will also fall back, permitting the side switch to pass to

third position; but, however, if the first 65 trunk is already in use, the private wiper 47 finds the first contact grounded, and thus completes an energizing circuit through the private magnet, locking the side switch in second position, thus permitting the rotary 70 magnet to once more energize and deenergize, stepping the shaft wipers onto another contact. The locking circuit of the private magnet 55 extends from the grounded private bank contact over wiper 47, through 75 side switch wiper 53 (in second position) and through magnet 55 to the battery lead 97. The rotary magnet continues to advance the wipers step by step until the private wiper 47 engages the non-grounded 80 contact of an idle trunk, whereupon the private magnet 55 deenergizes and allows the side switch to pass from second to third position. When the side switch leaves the second position the wiper 52 breaks the operating circuit of the rotary magnet.

85 The relay 115 energizes in series with the rotary magnet, but, being slow acting, remains energized for a short time after the rotary magnet has deenergized for the last 90 time. Thus the seized trunk is provided with a guarding potential the instant that the side switch passes to third position. Thus guarding potential extends from ground G^7 over springs 118 and 119, side switch wiper 95 53 and private wiper 47 to the private bank contacts. When the side switch wipers 51 and 54 pass from second to the third position the line relay 56 of the selector E is disconnected from the line, and the trunk lines 100 13 and 12 are extended by means for the trunk conductors 120 and 121 to the repeater F of Fig. 2. The circuit is then completed through the double-wound line relay 68 of the repeater F, said circuit extending from 105 ground G^8 through springs 122 and 123, lower winding of relay 68, springs 124 and 125 to trunk line 121, over said trunk line, shaft wiper 48, side switch wiper 54 and then over the same circuit through substation, as 110 was previously traced, back through side switch wiper 51, shaft wiper 46, conductor 120, springs 126 and 127, and through the upper winding of relay 68 to battery lead 97, thence through battery B to ground G. The 115 relay 68 energizes and closes the circuit of relay 69. This circuit extends from ground G^{10} through springs 128 and 129 and relay 69 to battery lead 97. The engagement of springs 130 and 131 by the energization of 120 relay 68 closes an energizing circuit through the double-wound relay 132 of the selector H. This circuit extends from ground G^{15} through lower winding of relay 132, side switch wiper 133, conductor 134, conductor 125 135 to and through springs 130 and 131, relay 136, upper winding of relay 72, conductor 137, conductor 138, side switch wiper 139,

upper winding of relay 132 to battery lead 140, thence through battery to ground. Relay 136 energizes to short-circuit relay 71 by closing springs 141 and 142, thus placing 5 ground G¹¹ on the opposite side of relay 71 from ground G¹².

When the relay 69 energizes upon the closure of its circuit by the energization of relay 68, a circuit is closed extending from 10 ground G⁸ through springs 122 and 143 and through the lower winding of relay 72 to the battery lead 67. Although both windings of relay 72 now carry current, the relay is not operatively energized, because the current flows through its windings in opposite 15 directions at this time. The engagement of springs 122 and 143 of the relay 69 also provides a new guarding potential for the selector private bank contacts of the trunk, 20 and provides a holding circuit for the release relay 101 of the selector E as soon as the guarding relay 115 de-energizes. This circuit extends from ground G⁸ through springs 122 and 143 to the selector private bank contacts, 25 thence over private wiper 47, through side switch wiper 53, springs 119 and 114^a of relay 115, and through relay 101 to battery lead 97. The relay 101 is slower to de-energize than the relay 115, so that this latter 30 circuit is closed before relay 101 has time to de-energize. The energization of the two relays 69 and 136 of the repeater F shifts the holding ground of relay 68 from ground G⁸ to ground G¹¹.

35 The apparatus is now in readiness to receive the impulses from the substation for the second digit 2. These impulses are repeated by the repeater F to the selector H, which operates to raise its shaft and wipers 40 144, 145 and 146 two steps and stop the same opposite the second row of bank contacts. The operation is as follows: The circuit of the line relay 68 of the repeater F is broken twice in response to the operation of the substation dial for the digit 2, thus permitting 45 the said relay 68 to twice momentarily de-energize, causing an energizing circuit to be established through the relay 70, which immediately energizes. This circuit extends 50 from ground G¹⁰ through springs 128 and 148, springs 149 and 150, 152 and 151 and relay 70 to battery lead 97, and thence through the battery B to ground G. The relay 69 being slow acting does not de-energize 55 during the momentary interruption of its circuit at the springs 128 and 129. The energization of relay 70 serves to disconnect the condensers 153 and 154 from the conductors 138 and 134, and also serves to short- 60 circuit the relay 136 and upper winding of relay 72 by the engagement of springs 155 and 156. The engagement of springs 157 and 158 supplies the ground connection to replace the ground G¹¹ which is disconnected 65 by the de-energization of relay 136 when it is.

short-circuited. Although only the lower winding of relay 72 carries current while the upper winding is short-circuited, this current is not strong enough to attract the armature of the relay.

70 The separation of the springs 130 and 131 by the de-energization of the repeater line relay 68 breaks the circuit of the selector line relay 132 by opening the bridge across the trunk conductors 138 and 134. Since 75 the digit called is 2, the circuit of relay 132 is thus broken twice momentarily. The relay 70 of the repeater being slow acting remains energized during the entire time impulses are being repeated, and thus maintains 80 the short-circuit of relay 136 and upper winding of relay 72 to prevent them from being included in the operating circuit of relay 132. Each time the relay 132 is de-energized a circuit is closed extending 85 from ground G¹⁰ through springs 160 and 159, 163 and 162, slow-acting relay 164, vertical magnet 147 and side switch wiper 165 to the battery lead 140, thence through the battery B to ground G. The vertical- 90 magnet 147 is thus energized twice, and operates to raise the switch shaft and wipers carried thereby two steps. As soon as the shaft is lifted from its lowest position the arm 168 is lifted, allowing spring 169 to 95 engage spring 170, which puts battery on one side of release magnet 167. The energization of relay 164 completes an energizing circuit through private magnet 171. This circuit extends from ground G¹⁰, springs 172 and 100 173 and magnet 171 to battery, thence through battery to ground. The relay 164 being a slow relay does not de-energize during the momentary breaking of its circuit between impulses, but does de-energize at 105 the end of the operation of the substation dial for the second digit, thereby permitting the private magnet to also de-energize, which allows the side switch to pass to second position. The side switch, in passing from first 110 to second position, disconnects the battery from the vertical magnet 147 and closes a circuit through the rotary magnet 174. This circuit extends from ground G¹⁵ through interrupter springs 175, rotary 115 magnet 174, relay 176 and side switch wiper 165 to battery lead 67, thence through battery B to ground. The rotary magnet, upon energizing, operates to rotate the wipers one step, to press down the private magnet armature, and to open its own circuit at the interrupter springs 175. When the rotary magnet circuit is thus opened the rotary armature falls back. If the first 120 trunk upon the contacts of which the wipers have just been rotated is not busy the private armature follows the rotary armature and permits the side switch to pass to third position. If the first trunk is busy, however, the shaft will be rotated another 125 130

contact, just as described for the first selector. As the side switch passes to third position the wiper 178 places a guarding potential on the private bank contacts. This extends from ground G^{18} through springs 179 and 180, wiper 178 (in third position) and private wiper 145 to the private bank contacts. This potential serves to keep another switch from stopping on a corresponding contact during the time that the side switch wipers are passing to the third position, and also during the time that the relays 73 and 181 of the connector are energizing. As soon as the relay 181 energizes it places a guarding potential back over conductor 183, to replace that just described, as soon as the slow relay 176 deenergizes, and also supplies a ground for the release relay 166 of the second selector H. Therefore, the holding circuit for relay 166 now extends from ground G^{20} through side switch wiper 188, springs 190 and 189 to conductor 183, shaft wiper 145, side switch wiper 178, springs 180 and 191 to and through relay 166 to battery. As soon as the side switch wipers 183 and 189 pass to third position, the trunk lines 134 and 138 are extended to the trunk lines 184 and 182 which lead to the connector I. The extension of these trunks completes an energizing circuit through the double wound line relay 73 of the connector. This circuit extends from ground G^{21} through the side switch wiper 192, lower winding of relay 73, springs 193, and 194, conductor 184, selector wiper 146, side switch wiper 183, conductors 134 and 135, thence through relays 136 and 72 of the repeater F in the same manner as traced for the relay 132, thence back over trunk conductors 138 and 182, through springs 195 and 196, and upper winding of relay 73 to battery lead 140. The relay 73, upon energizing, operates to close an energizing circuit for relay 181, which in turn energizes and extends a ground connection back over the conductor 183, as already described. The relay 181 also maintains the circuit of release magnet 77^a open by separating springs 197 and 198, and connects the impulse spring 185 with the vertical magnet 74 through the springs 197 and 199 and relay 200.

The foregoing is the operation of the apparatus for the first two digits. The connector I is now in position to respond to the operation of the substation calling device for the third digit 2. The operation of the calling device for this digit twice breaks the circuit of the repeater relay 68. The relay 68 operates to repeat two impulses to the connector line relay 73 in the same manner in which two impulses were repeated to the relay 132 for the second digit. Each time the relay 73 deenergizes a circuit is closed extending from ground G^{19} through

springs 186 and 185, 197 and 199, relay 200, vertical magnet 74 and side switch wiper 201 to battery lead 140. The vertical magnet operates, as in the selector switches, to raise the shaft and shaft wipers two steps opposite the second level of bank contacts. The slow relay 200 being in series with the vertical magnet operates to close an energizing circuit through the private magnet 76. This circuit extends from ground G^{22} through springs 205 and 206 and magnet 76 to battery B, thence through battery to ground. The relay 200 being slow acting does not deenergize during the momentary interruption of the current by springs 185 and 186, but does deenergize after the two impulses are sent in, thus permitting the private magnet to deenergize, which allows the side switch to pass to the second position. The release magnet 77^a is connected to battery in the same manner as in the selectors—that is, after the shaft is raised from its lowest position, the arm 208 permits springs 209 to engage spring 210, thus connecting said magnet to battery. 90

As the side switch wiper 201 passes to second position, battery is disconnected from the vertical magnet 74 and connected to the rotary magnet 75. The apparatus is now ready for the last digit 0. The relay 73 responds, as before, to the breaking of its circuit by the repeater, in response to the substation calling device, to operate the rotary magnet 75 over practically the same circuit as it did the vertical magnet 74. The rotary magnet operates to rotate the shaft and shaft wipers ten steps onto the terminals of the called line #2220. If the called line is not busy the private magnet deenergizes and permits the side switch wipers to pass to third position. When the wiper 188 passes to third position, the holding ground for relay 166 of the selector H is shifted from ground G^{20} to ground G^{19} . The passing of wiper 192 to third position shifts the circuit of relay 73 from ground G^{21} to ground G^{23} , thus placing the high resistance relay 79 in series with the relay 73. The relay 79 energizes to place the springs 211 and 212 in engagement, thus connecting ground G^{24} onto the relay 181 in case the relay 73 should deenergize sufficiently to allow its armature to fall back, thereby disconnecting ground G^{19} from relay 181. The wiper 213, in passing to third position, puts a guarding ground on the private bank contact to prevent the called line from being called by another subscriber, and also grounds the normal conductor which leads to the winding 214 of the line switch C'. This winding attracts the cut-off armature 215, which disconnects ground and the line winding of switch C' from said line and, by engagement of springs 216 and 217, extends the line conductor 218 from wiper 130

202 to the called substation. The wiper 213 also connects ground to the relays 77 and 81. The wiper 220 (in third position) extends the conductor 225 from the ringer relay springs to the called substation. The wiper 201 (in third position) places battery on the relay 77 and also completes an energizing circuit for the ringer relay 78. This circuit extends from ground G^{25} through 5 interrupter 221, relay 78, springs 223 and 222 and wiper 201 to battery B, thence through battery to ground. The relay 78, upon energizing, disconnects the calling and called lines and connects the ringer generator L with the called line to ring the bells 224. Since the circuit of the ringer relay includes the interrupter 221, the said relay is energized only intermittently so as not to ring the called substation continuously. 10

When the called subscriber removes his receiver, or as soon thereafter as the ringer relay deenergizes, if it happens to be energized at the time, the called substation is provided with talking current over a circuit 15 extending from ground G^{26} through side switch wiper 213, lower winding of relay 77, conductor 225, springs 227 and 226, side switch wiper 220, shaft wiper 204, conductor 219, springs 228 and 229, impulse springs 20, receiver 232, transmitter 231, springs 216 and 217, conductor 218, wiper 202, springs 233 and 234, 235 and 236, upper winding of relay 77 and wiper 201 to battery B, thence through battery to ground. 25

The relay 77, upon energizing, short-circuits the high resistance relay 79 by the closure of springs 300 and 301, and completes an energizing circuit through relay 81 by the engagement of springs 237 and 238. This 30 circuit extends from ground G^{26} through wiper 213, relay 81 and springs 237 and 238 to battery. The energization of relay 81 performs three functions: First, the engagement of the springs 239 and 222 forms a 35 locking circuit for the relay 81, which circuit extends from ground G^{26} through side switch wiper 213, relay 81, springs 239 and 222 and side switch wiper 201 to battery lead 140. Second, the disengagement of 40 springs 222 and 223 breaks the energizing circuit of the ringer relay. Third, the engagement of springs 194 and 195 with springs 247 and 246, respectively, reverses the direction of the current flowing over 45 conductors 182 and 184. As a consequence the direction of the flow of current through the upper winding of relay 72 of the repeater F is reversed, which relay now attracts its armature to bring springs 125 and 50 126 into engagement with springs 248 and 249, respectively. The engagement of these springs reverses the direction of the flow of current over conductors 120 and 121, but, as in the connector, it does not reverse the direction of the current through the double- 55

wound line relay. This reversal of the current in the conductors 120 and 121 causes the attraction of the meter magnet armature 62, as the current of the two windings of relay 63 are now assisting each other. 70 The attraction of this armature causes the meter to register once by means of the pawl on the armature 62 engaging the ratchet wheel 61 of the meter. It will be remembered that the relay 81 of the connector controls its own circuit; therefore, the meter will only register once no matter how many times the receiver at substation A' is lifted from its hook. The attraction of the armature 62 also closes the springs 66 and 67 75 into engagement, thereby short-circuiting the winding 64, but as the winding 65 is still energized it serves to hold the armature 62 in an operated position. 80

After the conversation is completed the 85 release of the central office apparatus used in the connection is initiated by the restoration of the receiver at the calling substation. When the springs 85 and 87 of substation A are disengaged by placing the receiver on 90 the hook, the energizing circuit of the relay 68 of the repeater F is broken, thus allowing it to deenergize. The separation of springs 128 and 129 breaks the energizing circuit of the relay 69. This relay deenergizes to dis- 95 connect the holding ground from the release relay 101 of the selector E. The deenergization of relay 101 closes an energizing circuit through the release magnet 57 over the following circuit: Ground G^3 , springs 98 and 100 99, 103 and 102, magnet 57 and springs 58 and 59 to battery. This circuit is broken again by the springs 58 and 59 when the shaft reaches its lowest position. The deenergization of relay 101 also breaks the 105 holding circuit of the winding 17 of line switch C, which deenergizes and allows the plunger arm to be restored to normal position, thus breaking the energizing circuit of the winding 65 of the meter magnet, whose 110 armature is also restored to normal position. The release of the second selector and connector is quite similar to that of the first selector. The deenergizing of the line relay 68 of the repeater F opens the circuit of the 115 line relay 73 of the connector, which deenergizes to break the holding circuit of the release relay 181 of the connector and of relay 166 of selector H. The relay 166, upon deenergizing, closes the circuit of the release 120 magnet 167, as in the first selector E. The engagement of springs 197 and 198 of relay 181 closes a circuit through the release magnet 77^a of the connector over the following 125 circuit: ground G^{19} , springs 186 and 185, 197 and 198, magnet 77^a, springs 209 and 210 to battery B, thence through battery to ground. The connector, upon restoring to normal position, breaks the circuit of the winding 214 of line switch C' at the private 130

wiper 203; thus all the switches are now in readiness for another call.

In case a line is already busy when called, the calling subscriber is given the busy signal in the following manner: As has been explained, whenever a line is busy there is a guarding ground potential upon its connector private bank contacts. Thus, when the relay 200 of the connector I deenergizes, 10 with the private wiper 203 resting upon the private bank contact of a busy line, a circuit is closed extending from ground at said private bank contact, thence over wiper 203, side switch wiper 213 (which is then in 15 second position), springs 243 and 242, relay 80, springs 207 and 206, and private magnet 76 to battery lead 140. The spring 206 engages springs 207 before it breaks contact with spring 205, and thus the energizing 20 circuit of the private magnet is not broken when the relay 200 deenergizes. The private magnet therefore remains energized, locking the side switch in second position, and at the same time relay 80 is energized in series 25 therewith. When relay 80 energizes, the spring 242 engages spring 241 before breaking contact with spring 243, thereby shifting the holding ground for relay 80 and private magnet 76 from the private wiper 203 to 30 ground G²⁰. This circuit extends from ground G²⁰ through side switch wiper 188, springs 190 and 189, springs 241 and 242, relay 80, springs 207 and 206 and magnet 76 to battery. The disengagement of springs 239 35 and 240 of relay 80 breaks the circuit of the rotary magnet 75. The calling subscriber now receives the busy signal over the circuit extending from battery through secondary winding of induction coil 83, springs 245 and 244, side switch wiper 220, springs 226 and 227, conductor 184, through substation A, back over conductor 182, springs 195 and 196, upper winding of relay 73, thence to the battery lead to the starting point. The 40 primary busy circuit extends from ground G²⁷ through an interrupter 82, primary or induction coil 83 to battery, thence through battery to ground. While the calling subscriber is receiving the busy signal, the connection with the called line is open on one side at the side switch wiper 220, and on the other side at the private magnet springs 235 and 236. The switches are released from this position by the hanging up of the receiver at the calling substation in practically 55 the same manner as when the called line was idle.

The rotary connector I' shown in Fig. 4 is, as before mentioned, quite similar to the 60 connector switch shown in Fig. 3. The rotary connector switch is controlled by the calling subscriber over trunk lines leading from the banks of the selector H. The repeater F works in conjunction with this 65 rotary connector the same as with connector I. This type of connector is used where a business house or private branch exchange, for instance, desires to have a plurality of trunk lines extending to the central office, but wishes to be given only one number. 70 This connector is so arranged that if the first of these trunks or lines is in use, it will automatically extend the calling subscriber's line into connection with the second line; if the second line is also busy the connection will be extended to the third line, and so on. The calling subscriber would, of course, have no control over the apparatus as to with which one of the lines he may make connection. This, however, does not 75 concern him, since any trunk line to the said office or private branch exchange will serve his purpose. The arrangement of the connector banks will be as follows: Suppose, for instance, that the office or business house 80 to which the number 2121 has been assigned wishes three telephones, it will be given three lines, one terminating in the first contact of the second level of the connector banks, the second in the second contact of 85 the second level, etc. Now suppose, for instance, that the substation A, instead of calling #2220 as was heretofore described, calls the number 2121. The action of the line switch, first selector and repeater is the 90 same as before. The shaft of the second selector, however, instead of being raised two steps as before, will, in response to the calling device for the second digit 1, be raised only one step and, as before, automatically rotated one step onto the terminals of a trunk line leading to the said rotary connector. The operation of the connector in response to the calling device for the last two digits is as follows: The circuit of the double-wound relay 248 is broken twice in response to the calling device, or, 95 more strictly speaking, since the calling device controls the repeater, in response to the repeater. The deenergizing of relay 248 100 closes an energizing circuit through the vertical magnet 249 in series with the slow relay 84. The circuit extends from ground G²⁸ through springs 251 and 250, 252 and 253 (as the relay 254 is energized), slow relay 84, vertical magnet 249 and side switch wiper 255 to battery B, thence through battery to ground. The vertical magnet energizes to raise the shaft and shaft wipers 105 two steps opposite the second level of bank contacts. The energizing of the relay 84 110 closes an energizing circuit through the private magnet 256, which relay, upon deenergizing, allows the side switch to pass to second position. The passing of the side switch wiper 255 to the second position switches battery from the vertical magnet 249 to rotary magnet 269. The calling device is now operated for the last digit (1). 115 The rotary magnet responds by rotating 120

125 130

the shaft one step onto the first bank contact. As before stated, this is the first of the lines leading to the called subscriber. If this contact is not busy the side switch 5 passes to third position in the usual manner, completing the line connection to the called substation and placing a guarding ground on the private bank contact over a circuit extending from ground G^{29} through 10 side switch wiper 257, relay 258, springs 259 and 260 to private wiper 261. This prevents another connector from stopping on this contact. In case the first contact is 15 busy, however, the wiper 261 will find the first contact grounded. Then, as soon as the relay 84 deenergizes, a circuit is completed extending from the ground at the private wiper 261 through springs 260 and 259, relay 258, side switch wiper 257 (in 20 second position), springs 263 and 262, private magnet 256 to battery, thence through battery to ground. The relay 258 does not energize over this circuit. The private magnet 256, however, remains energized after 25 relay 84 deenergizes, completing a circuit extending from ground G^{30} through interrupter 264, springs 265 and 266, 267 and 268, rotary magnet 269 and side switch wiper 255 (in second position) to battery 30 B, thence through battery to ground. This interrupted current through the rotary magnet operates to energize the rotary magnet, which in turn rotates the shaft one step onto the second bank contact. If this contact is 35 idle the private magnet deenergizes and the side switch passes to third position in the usual manner. If the second contact is also busy the shaft will continue to rotate until the private wiper finds an idle contact. 40 Should all of the trunk lines be busy the subscriber is given the busy signal as follows: The shaft wipers are rotated over all of the busy trunk lines, such as 270, 271, and 272, but stop on the next adjacent contacts 45 273, 274 and 275. The private contact 274 is connected through a resistance to battery. The contact 273 may be dead, while the contact 275 is connected through a relay 276 to battery. As the connector 50 wipers pass onto the contact 274 the private wiper is shifted from ground to battery through the resistance 277. This allows the private magnet to deenergize, which in turn allows the side switch to pass to the third 55 position. A circuit is then completed extending from ground G^{29} through the side switch wiper 257, relay 258, springs 259 and 260, private wiper 261 and resistance 277 to battery B. The relay 258, upon energizing, causes the spring 259 to engage the spring 278 a short time before breaking from the spring 260. This is to allow a new circuit to be established through the relay 258 before the old circuit is broken. 60 65 This new circuit extends from ground G^{29}

through the relay 258, springs 259 and 278, private magnet 256 to battery. Although the current flowing through the relay 258 in series with the private magnet 256 is not sufficient to attract the armature of the relay from its normal position, it is sufficient to hold said armature in its operated position after it is once operated. The disengagement of the springs 259 and 260 disconnects ground from the private wiper, 70 thus allowing another subscriber to also stop on the contact 274 that he may receive the busy signal. The relay 276 energizes over a circuit extending from ground G^{29} through the lower winding of the relay 279, ringer 80 springs 281 and 280, side switch wiper 282, shaft wiper 283, contact 275 and relay 276 to battery, thence through battery to ground. This relay, upon energizing, gives the subscriber the busy signal over the following circuit: battery, secondary of induction coil of the busy machine O', springs 285 and 284, contact 275 and wiper 283, then over the same circuit as described in connection with the connector I. The other 90 features of this connector are essentially the same as in the connector I. Of course, it is evident that another group of lines could be connected to the contact beginning with the set of contacts following the contacts 95 273, 274 and 275. To obtain connection with one of these lines it would be necessary to call #2125, assuming contacts 273, 274 and 275 are the fourth set, as shown in the drawings. As shown in Fig. 5, the cord circuit R consists essentially of the answering plug p and calling plug p' , supervisory relays 287 and 288, lamps 289 and 290, repeating coil N, key K, operator's set M and calling device 291. A magneto telephone is 100 also shown at substation A' in Fig. 5. It will now be explained how supervision is brought about in the cord circuit in case the subscriber at the manual substation A' calls the subscriber A'. The subscriber A' 110 removes his receiver and operates the hand generator 292 in the usual manner, which places a current on the conductors 293 and 294 to operate the drop 295. The operator inserts the plug p into jack j in response to 115 the signal, and throws the key K, thereby cutting her set into the circuit. Upon learning the number desired by the calling subscriber, the operator inserts the plug p' into the jack j' . The trunk conductors 298 and 120 299 of the jack j' lead to a line switch C' in the same manner that the line conductors 12 and 13 lead to the line switch C. The line switch C' is in all respects similar to the line switch C, except that the normal 125 conductors may be omitted. The line switch C' has access to first selector switches in the same manner as the line switch C, through the medium of which the operator is enabled to set up any desired automatic connection. 130

By throwing the key K' the operator disconnects the talking set M and windings 296 and 297 of the repeating coil N from across the trunk conductors 298 and 299, and connects the calling device 291 across the trunk instead. The operator now sets up the call through the line switch C², selector E, repeater F, selector H and a connector I in exactly the same manner, and the operation 10 of said switches is the same, as when the subscriber at substation A called substation A'. It will be remembered that when the connector side switch 192 passed from second to third position, the high resistance relay 15 79 was included in series with the double-wound line relay 73, and consequently in series with the relays 136 and 72 of the repeater F. The relay 136 does not receive enough current when connected in series 20 with relay 79 to be operatively energized; consequently, when the relay 70 of the repeater deenergizes after the last digit is called, the high resistance relay 71 is included in circuit with the double-wound line 25 relay 68. When the operator restores the key K after completing the call, the relay 288 is bridged across the line and thus is connected in a series circuit with relays 71 and 68 at the repeater F. The relay 288 30 does not receive enough current when connected in series with relay 71 to be operatively energized, and does not break the circuit of the lamp 290 which was closed as soon as the plug p' was inserted into jack 35 j'. This circuit extends from ground G³⁰ through sleeve of jack j' and plug p', springs 305 and 304, contact 306, armature 308 and lamp 290 to battery B, thence through the battery to ground. The energization of the 40 relay 71 at the repeater F provides a new holding ground for the relay 69, maintains the bridge across the trunk conductors 134 and 138 closed and prevents the closure of the circuit of relay 70 in case the line relay 68 45 allowed its armature to fall back when relay 71 enters its circuit. When the called subscriber removes his receiver the back-bridge relay 77 energizes and short-circuits the relay 79 in the same manner as when substation A' was called by subscriber at substation A. When the relay 79 is short-circuited it reduces the resistance of the circuit of relay 136 of the repeater F sufficiently to allow said relay to operatively energize. 50 The energization of relay 136 serves to short-circuit the relay 71, which reduces the resistance of the circuit of the repeater line relay 68 and of the supervisory relay 288 of the cord R sufficiently to cause these relays to 55 be operatively energized. The energization of relay 288 breaks the energizing circuit of the lamp 290, which signifies to the operator that the called subscriber has answered. When the called subscriber hangs up his 60 receiver upon the termination of the conver- sation, the connector back-bridge relay 77 deenergizes and removes the short-circuit from relay 79. The relay 79 thus again enters the circuit of the relay 136, which then allows its armature to fall back, removing 70 the short-circuit from the relay 71. This reduces the flow of current through the supervisory relay 288 sufficiently to cause its armature to fall back and again close the circuit of lamp 290. The line switch C² is 75 provided with a meter like the meter J (Fig. 1). This meter is operated by the reversal of the current when the called subscriber removes his receiver in the same manner as explained for the meter J when a call was 80 made from substation A.

Supervision in the other side of the cord is taken care of by the relay 287 in the usual manner. This relay is energized through its right-hand winding by current from the 85 substation generator 292. When the relay 287 is thus energized it forms a locking circuit for itself extending from ground G³¹ through sleeve of jack j and plug p, springs 310 and 309, contact 311 and winding 312 90 to battery B. The lamp 289 is then lighted over a circuit extending from ground G³¹ through sleeve of jack j and plug p, contact 313 and lamp 289 to battery B. Upon the removal of the plugs from the jacks both 95 lamps are extinguished and the selector and connector switches and the repeater are restored to normal position, just as when the receiver at the calling substation A was restored to the switch hook in the first connection described. 100

It will be noted that the rotary connector I' is supplied with a high resistance relay 314 which is similar to relay 79 of connector I, and a supervision is obtained through 105 connector I' in the same manner as through connector I.

It will be understood, of course, that the supervisory relays 79 and 71 of the connector I and repeater F operate in the same manner when an automatic subscriber calls as when a manual operator sets up the call. The operation of these relays is without any particular function, however, when the 110 call comes from an automatic substation, as 115 the insertion of a resistance in the line before a subscriber answers has no effect on the meters.

From the foregoing it will be seen that I provide a system in which the subscribers 120 are given measured service, and in which toll is assessed by a mechanism which is responsive to the reversal of current in the talking circuit. The reversal of the current may be in the calling subscriber's line, or 125 in a part of the talking circuit between the calling and called lines, depending upon the conditions and requirements of any particular case. For this purpose, as explained, a connector is provided having means for 130

reversing the current in the talking circuit—that is to say, in that portion of the talking circuit which is between the calling subscriber and the connector. The said connector may be one for ordinary use, or it may be a rotary connector of the kind shown and described. Furthermore, the said connector may be of the kind in which provision is made for decreasing the flow of current in the talking circuit when the called line is found to indicate to an operator that the connection has been established, and for then retiring the supervisory signal when the called subscriber answers. Thus two things may be accomplished by the response of the called subscriber, to-wit, the giving of a supervisory signal and the registering of the call, or the operation of any other suitable mechanism for any suitable purpose. Furthermore, it is obvious that the reversal of current in the talking circuit may be accomplished by other suitable means, and not by means in the connector, without departing from the spirit of my invention. Any automatic switch for use in an automatic or semi-automatic telephone exchange system which has provision for reversing the flow of current in the talking circuit will serve the purpose of my invention. Also, it will be seen that my invention is operative in connection with a system in which the automatic switches are controlled over metallic circuits—that is to say, by controlling the two sides of the calling line in series. Again, it is preferable that my improved system be of the kind in which the current for talking purposes is supplied from a central source, or from one or more central sources, when the call is from one automatic subscriber to another. As shown, however, local batteries may be employed for the manual substations, and it is contemplated that other arrangements may be employed for supplying talking current without departing from the spirit of my invention.

It will be seen that the selectors and connectors of my improved system are of that type in which one motion is employed for selecting a group and another motion for then finding a line in the predetermined group. In the selectors, for example, the vertical motion is employed for selecting a group of trunks corresponding to the digit of any called number, and the rotary motion is then employed for automatically selecting an idle trunk in the predetermined group. In the connectors the vertical motion is employed for selecting a group of subscribers' lines in accordance with a digit of the called number, and the rotary motion is then employed for finding the called line in accordance with another digit of the called number. The system is of the two-wire type, to-wit, a system which is free

from operating grounds at the substations thereof. As described and illustrated, the calling connection may be either entirely automatic or semi-automatic, and in the latter case the originating operator has complete supervision of the connection. In either case, however, the call is registered by a measured service device of any suitable character which responds to a reversal of current in the talking circuit when the called subscriber answers. The measured service device may be located at any suitable point in the connection, depending upon the purpose for which it is employed.

In telephone systems giving so-called measured service, it is very often desired that no charge shall be levied for calling certain lines, such as lines which terminate at the central office and over which operators or exchange attendants are called, etc. In systems employing meters which are operated automatically when the called subscriber answers, this requires that special means be provided to prevent the meter of the calling line from being operated when a call to a free line is answered. This may be very easily accomplished in the system shown herein by making all such lines which are to be called free accessible by special connector switches. This special connector can be merely the ordinary form of two-wire connector—that is, a connector which does not have any provision for reversing the current upon the line. For example, these special connectors may be similar in all respects to the connector I (Fig. 3), with the exception that the windings of the line relay 73 should be connected to the trunk conductors 182 and 184 direct and not through the springs of the relay 81. The relay 81 of these special connectors would then have no springs corresponding to the springs 193, 194, 247, 196, 195 and 246. When any line is called over such a connector, the response at the called substation does not cause the current in the calling line to be reversed, and consequently the meter of the calling line is not operated. Thus, any line in the system can call any line which is accessible from these special connectors without being charged for the call.

What I claim as my invention is:

1. In a telephone system, a manual switchboard, means including a repeater and a connector for extending connection therefrom, said connector and repeater provided with means for reducing the flow of current in the talking circuit when the called line is found, a signal at the manual switchboard, which signal is responsive to said reduction of current in the talking circuit, and means for retiring said signal when the called subscriber answers.

2. In a telephone system, a manual switchboard, means including a repeater and a

connector for extending connection therefrom, said connector and repeater provided with means for reducing the flow of current in the talking circuit when the called line is found, a signal at the manual switchboard, which signal is responsive to said reduction of current in the talking circuit, means for retiring said signal when the called subscriber answers, and a central 10 source of talking and operating current.

3. In a telephone system, a manual switchboard, means including a repeater and a connector for extending connection therefrom, said connector and repeater provided 15 with means for reducing the flow of current in the talking circuit when the called line is found, a signal at the manual switchboard, which signal is responsive to said reduction of current in the talking circuit, 20 and means for retiring said signal when the called subscriber answers, said system being free from operating grounds at the substations thereof.

4. In a telephone system, the combination 25 with an operator's position and a called telephone line, of means for extending a connection therebetween, a supervisory signal at the operator's position, a plurality of serially related closed supervisory control 30 circuits, a marginal relay in the first of said circuits controlling said signal, a marginal relay in the second of said circuits controlling the resistance of the first circuit, and means controlled over the called line 35 for controlling the resistance of said second circuit.

5. In a telephone system, an established connection extending through an operator's position and including a plurality of serially 40 related trunk lines and a called telephone line, a plurality of serially related closed supervisory control circuits each including a trunk line conductor, a supervisory relay at the operator's position in the first of said 45 circuits and irresponsible to the normal current flow therein, means controlled over the called line for increasing the current flow in the second of said closed circuits, and a marginal relay responsive to such current 50 increase for in turn increasing the current in said first circuit.

6. In a telephone system, an established connection extending through an operator's position and including a plurality of serially 55 related trunk lines and a called telephone line, a plurality of serially related closed supervisory control circuits each including a trunk line conductor, a supervisory relay at the operator's position in the first of 60 said circuits and irresponsible to the normal current flow therein, means controlled over the called line for increasing the current flow in the second of said closed circuits, a marginal relay responsive to such current 65 increase for in turn increasing the current

in said first circuit, whereby said supervisory relay may be operated, and a signal controlled by said relay.

7. In a telephone system, an established connection between a calling and a called line including an operator's cord circuit and a plurality of trunk lines, serially related closed supervisory control circuits each including a trunk line conductor, a supervisory relay in the first of said closed circuits sensitive to resistance changes therein, means controlled over the called line for altering the resistance of the other of said closed circuits, and means responsive to such alteration of resistance for altering the resistance of said first circuit to affect said relay.

8. In a telephone system, an established connection between a calling and a called line including an operator's cord circuit 35 and a plurality of trunk lines, serially related closed supervisory control circuits each including a trunk line conductor, a supervisory relay in the first of said closed circuits sensitive to resistance changes therein, a second relay controlled over the called line for altering the resistance of the other of said closed circuits, a third relay responsive to such alteration of resistance for altering the resistance of said first circuit to 90 operate said first relay, and a signal in said cord circuit controlled thereby.

9. In a telephone system, an established talking connection between a calling and a called line including an operator's cord circuit and an automatic switch, serially related closed supervisory control circuits each including a talking conductor, a supervisory relay in the first of said circuits sensitive to resistance changes therein, and a relay 100 in the second of said circuits sensitive to resistance changes therein for altering the resistance of the said first circuit.

10. In a telephone system, an established talking connection between a calling and a called line including an operator's cord circuit and an automatic switch, serially related closed supervisory control circuits each including a talking conductor, a supervisory relay in the first of said circuits sensitive to resistance changes therein, a relay in the second of said circuits sensitive to resistance changes therein for altering the resistance of the said first circuit, and means controlled over the called line for altering the resistance of said second circuit.

11. In a telephone system, an established talking connection between a calling and a called line including an operator's cord circuit and an automatic switch, serially related closed supervisory control circuits each including a talking conductor, a supervisory relay in the first of said circuits sensitive to resistance changes therein, a relay in the second of said circuits sensitive to resistance changes therein 125

- changes therein for altering the resistance of said first circuit, and a relay in said switch controlled over the called line for altering the resistance of said second circuit.
- 5 12. In a telephone system, a temporarily established connection comprising three inductively connected sections, including, respectively, an operator's cord circuit, an automatic switch, and a called telephone line,
- 10 serially related closed supervisory control circuits including, respectively, conductors of the first two sections, a third circuit including a conductor of the third section, a supervisory relay in the first circuit, and
- 15 means in each circuit except the first for effecting a change in the resistance of the preceding circuit, whereby said supervisory relay may be controlled from the called substation.
- 20 13. In a telephone system, a temporarily established connection comprising two inductively connected sections, an operator's cord circuit and a trunk line included in the first section, an automatic switch and a
- 25 called telephone line included in the second section, a supervisory relay in said cord circuit, a closed circuit for said relay including a conductor of said trunk line, and means actuated upon the response of the called subscriber for altering the resistance of said circuit to control said relay.
14. In a telephone system, a temporarily established connection comprising two inductively connected sections, an operator's
- 30 cord circuit and a trunk line included in the first section, an automatic switch and a called telephone line included in the second section, a supervisory relay in said cord circuit, a closed circuit for said relay including
- 35 a conductor of said first section, a second circuit including a conductor of said second section, and a second relay controlled over said second circuit for altering the resistance of said first circuit to control said first relay.
- 40 15. In a telephone system, a temporarily established connection comprising two inductively connected sections, an operator's cord circuit and a trunk line included in the first section, an automatic switch and a
- 45 called telephone line included in the second section, a supervisory relay in said cord circuit, a relay in bridge of said first section controlling said switch, a circuit including said relays in series, and means controlled
- 50 over the said second section for altering the resistance of said circuit to control said supervisory relay.
16. In a telephone system, a temporarily established connection comprising two inductively connected sections, an operator's
- 55 cord circuit and a trunk line included in the first section, an automatic switch and a called telephone line included in the second section, a supervisory relay in said cord circuit, a circuit for said relay including a
- 60 conductor of said first section, a resistance in said circuit rendering said relay inoperative, and a relay controlled over a conductor of the other section for short-circuiting said resistance.
- 65 17. In a telephone system, a temporarily established connection including an operator's cord circuit, a trunk circuit, and a plurality of serially related automatic switches connecting said trunk circuit with a called line, a relay in bridge of said trunk circuit controlling said switches, a supervisory relay at the cord circuit, a circuit including said relays in series, and means actuated upon the response of the called subscriber for altering the resistance of said circuit to control said supervisory relay.
- 70 18. In a telephone system, a temporarily established connection including an operator's cord circuit, a trunk circuit, and a plurality of serially related automatic switches connecting said trunk circuit with a called line, a relay in bridge of said trunk circuit controlling said switches, a supervisory relay at the cord circuit, a circuit including said relays in series, a resistance in said circuit, said supervisory relay rendered inoperative thereby, and means actuated upon the response of the called subscriber for short-circuiting said resistance.
- 75 19. In a telephone system, a temporarily established connection including an operator's cord circuit, a trunk circuit, and a plurality of serially related automatic switches connecting said trunk circuit with a called line, a relay in bridge of said trunk circuit controlling said switches, a supervisory relay at the cord circuit, a circuit including said relays in series, said circuit including also a resistance whereby said last relay is rendered inoperative, and means controlled over the called line for shunting out said resistance, whereby the said last relay is enabled to operate.
- 80 20. In a telephone system, a connection between a calling and a called line, a signal for indicating the response of the called subscriber, two coöperating closed control circuits in serial relation to each other, means controlled over the called line for altering the resistance of the last of said circuits, means responsive to such alteration for in turn altering the resistance of the first of said circuits, and means in said first circuit for controlling said signal.
- 85 21. In a telephone system, a connection between a calling and a called line, a signal for indicating the response of the called subscriber, two coöperating closed control circuits in serial relation to each other, means controlled over the called line for altering the resistance of the last of said circuits, means responsive to such alteration for in turn altering the resistance of the first of said circuits, and means in said first cir-
- 90 95 100 105 110 115 120 125 130

cuit for controlling said signal, said means comprising relays and resistances, together with connections controlled by the relays for cutting said resistances in or out of said 5 circuits.

22. In a telephone system, a line, an automatic switch for said line having bank terminals divided into groups, the groups being disposed in parallel planes, movable 10 arms having motion in one direction to find a group and motion in another direction to find a terminal in the selected group, a line relay for controlling the operation of said arms, means for controlling the two sides 15 of said line in series to control said relay, a local circuit governing the said second motion, normally closed contacts in said local circuit, which contacts are open during the said first motion, and means whereby 20 said contacts are then closed to control the second motion.

23. In a telephone system, an automatic switch having bank terminals divided into groups, the groups being disposed in parallel planes, movable arms having motion in one direction to find a group and motion in another direction to find a terminal in the selected group, an electromagnet for producing the first motion, an electromagnet for 25 producing the second motion, means for controlling the two sides of said line in series to control one of said magnets, a local circuit governing the said second motion, normally closed contacts in said local circuits, which 30 contacts are open during the said first motion, and means whereby said contacts are then closed to control the second motion.

24. In a telephone system, an automatic switch having bank terminals divided into 40 groups, the groups being disposed in parallel planes, movable arms having motion in one direction to find a group and motion in another direction to find a terminal in the selected group, electromagnet mechanism for 45 producing said first and second motions, a local circuit governing the said second motion, normally closed contacts in said local circuit, which contacts are open during the said first motion, and means whereby said 50 contacts are then closed to control the second motion.

25. In a telephone system, an automatic switch having bank terminals divided into groups, the groups being disposed in parallel planes, movable arms having motion in one direction to find a group and motion in another direction to find a terminal in the selected group, a line relay for controlling the operation of said arms, means for controlling 55 the two sides of said trunk in series to control said relay, a local circuit governing the said second motion, contacts in said local circuit, which contacts are open during the said first motion, and means whereby 60 said contacts are automatically closed upon 65

the cessation of the first motion to control the second motion, other contacts in said local circuit, and means whereby said other contacts are automatically opened to stop said second motion when the said terminal 70 is found.

26. In a telephone system, an automatic switch having bank terminals divided into groups, the groups being disposed in parallel planes, movable arms having motion 75 in one direction to find a group and motion in another direction to find a terminal in the selected group, an electromagnet for producing the first motion, an electromagnet for producing the second motion, means 80 for controlling the two sides of said line in series to control one of said magnets, a local circuit governing the said second motion, contacts in said local circuit, which contacts are open during the said first motion, means whereby said contacts are automatically closed upon the cessation of the first motion to control the second motion, other contacts in said local circuit, and means whereby said other contacts are automatically opened to stop said second motion when the said terminal 85 is found.

27. In a telephone system, an automatic switch having bank terminals divided into groups, the groups being disposed in parallel planes, movable arms having motion in one direction to find a group and motion in another direction to find a terminal in the selected group, electromagnet mechanism for producing said first and second 90 motions, a local circuit governing the said second motion, contacts in said local circuit, which contacts are open during the said first motion, means whereby said contacts are automatically closed upon the 95 cessation of the first motion to control the second motion, other contacts in said local circuit, and means whereby said other contacts are automatically opened to stop said second motion when the said terminal 100 is found.

28. In a telephone system, a link circuit for extending connection between calling and called lines, fixed terminals for said link over which said link is seized, movable 115 terminals for said link for extending the connection to a called line, a source of current, means for supplying current to said fixed terminals, means for supplying current to said movable terminals, and means 120 for reversing the current supply to said movable terminals.

29. In a telephone system, a link circuit for extending connection between calling and called lines, fixed terminals for said 125 link over which said link is seized, movable terminals for said link for extending the connection to a called line, a source of current, means for supplying current to said fixed terminals, means for supplying cur- 130

rent to said movable terminals, and means for reversing the current supply to said fixed and movable terminals.

30. In a telephone system, an automatic progressively movable switch for extending connection between calling and called lines, fixed terminals for said switch over which said switch is seized, movable terminals for said switch for extending the connection

to a called line, a source of current, means for supplying current to said fixed terminals, means for supplying current from said source to said movable terminals, and means for reversing the current supply to said movable terminals.

Signed by me at Chicago, Cook county, Illinois, this 10th day of March, 1917.

TALBOT G. MARTIN
